C. FISHER

GOLF CLUB

Filed April 6, 1921

Inventor:
Charles Fisher,
By appointment, Lee, Chapman & Miles,
Attys.

UNITED STATES PATENT OFFICE.

CHARLES FISHER, OF CHICAGO, ILLINOIS, ASSIGNOR, BY DIRECT AND MESNE ASSIGNMENTS, TO THE AUTOMATIC RECORDING SAFE COMPANY, OF CHICAGO, ILLINOIS, A CORPORATION OF ILLINOIS.

GOLF CLUB.

Application filed April 6, 1921. Serial No. 459,053.

To all whom it may concern:

Be it known that I, CHARLES FISHER, a citizen of the United States, residing at Chicago, in the county of Cook and State of Illinois, have invented a new and useful Improvement in Golf Clubs, of which the following is a specification.

This invention relates particularly to golf clubs; and the primary object is to provide a golf club having a collapsible shaft, enabling the club to be conveniently carried in a suit-case. A further object is to provide a golf club with a shaft of the character mentioned, which can be cheaply manufactured, which is strong and durable, and which can be changed from the collapsed to the extended condition, or vice versa, with great facility.

The invention is illustrated in its preferred embodiment in the accompanying drawing, in which—

Fig. 1 represents an elevational view of a golf club embodying the invention; Fig. 2, an enlarged broken sectional view of the shaft; Fig. 3, an end view of the lower section of the shaft; and Fig. 4, a broken sectional view, showing a modification.

The club comprises a club head A; and a shaft B, composed of telescopic sections. In the illustration given, the shaft B comprises a lower section B' which is secured to the club head in the usual manner, and a tubular handle-section B² having telescopic connection with the section B'.

The shaft-section B', in the illustration given, is formed of wood, and has its upper end fitted with a taper metal sleeve or ferrule 1. The upper end of the shaft-section B' is preferably reduced to receive the ferrule, as indicated at 2. The reduced end is provided with a bore 3, from which radiate slits 3^a. In the illustration given, the slits 3^a divide the upper end portion of the reduced section 2 into four sectors. A taper pin 4 is driven, as a wedge, into the central perforation 3, thus expanding the wood within the metal sleeve 1. Before the wedging operation is performed, the parts are entered so as to be in telescopic relation with the tubular handle B².

The handle B² preferably comprises a seamless steel tube 5, which has its upper portion equipped with a grip 5^a, and which has its lower portion tapered, as indicated

at 5^b. The grip 5^a may be composed of leather, rubber or any desirable material, applied to the outer surface of the handle portion proper of the tube 5. The upper end of the tube 5 is closed by a plug 6, which preferably has a reduced threaded portion 6^a extending into the tube and engaging internal threads with which the upper end of the tube is provided.

The taper fit between the sleeve 1 and the lower end 5^b is indicated at 7. The taper should be very gradual. The parts may be rigidly secured together in extended relation by a quick longitudinal jerk of the club, while the handle is grasped in the hand, the momentum of the lower portion of the club being sufficient to effectively wedge the parts together. It may be noted that in the action of swinging the club in driving a ball, the centrifugal force which results serves to wedge the parts more tightly together. The club may be collapsed by inverting it and tapping the handle against the pavement, for example, which will readily loosen the parts at the taper joint so that the shaft-section B' may then be almost completely telescoped within the handle-section B².

It may be added that the parts may be in this completely telescoped relation before the wedge 3 is driven in to expand the socket portion 2 of the shaft-section B'.

In the modification shown in Fig. 4, the same parts are used, and corresponding references are employed in Fig. 4. In this case, however, the wedge pin 4 is replaced by a wedge screw 4^a. Should it be desired, this wedge screw may be turned further in to cause expansion of the sleeve 1. This is a positive means for effecting a greater gripping action between the sleeve 1 and the lower portion 5^b of the tubular handle-section. In practice, however, this is unnecessary, inasmuch as, when a very gradual taper is employed, the joint shown in Fig. 2 is ample to secure the shaft-sections in extended rigid relation.

While the lower shaft-section B' preferably is of wood, it may be of steel or other material. Also, it is preferred to employ two shaft-sections of approximately the same length, which insures a desirable flexibility of the shaft. However, the shaft may be made in three sections if desired.

It will be noted that the club-head A is

of the usual angular form, and thus the club-head projects laterally from the axis of the shaft. Ordinarily, it would be assumed that it would be necessary to positively connect 5 the lower shaft-section B' with the tubular housing section B² against possibility of rotation. Experience has demonstrated, however, that by making the downwardly converging tapering surfaces between the ferrule 1 and the lower portion 5^b of the tubular member B² of exceedingly gradual taper, that is, diverging only very slightly from a true cylindrical surface, it is possible 10 to so wedge the inner member within the outer member by utilizing the inertia of the club-head and lower shaft-section when the handle section is jerked with relation thereto to so firmly bind the parts together as to 15 avoid all danger of angular movement of the members with relation to each other in the use of the club. Moreover, the centrifugal force which is the result of the inertia of the club-head and lower shaft-section when the club is swung tends to increase the wedging 20 effect. The handle section B², which is the housing section, is of larger diameter than the club-head section of the shaft. In other words, there is a general downward taper of the shaft as a whole. The housing section 25 B² and the club-head section B' are of approximately the same length, so that in the collapsed condition, the length is reduced to about one half. In effect, the upper end of the club-head section is expanded so that its 30 exterior diameter (measured across the ferrule 1) is greater than the internal diameter of the lower end of the portion 5^b of the tubular handle B². The ferrule 1 can, of course, be applied to the upper end of the 35 club-head shaft-section after the latter has

been inserted through the lower end of the tubular handle and the parts brought to the collapsed position.

The foregoing detailed description has been given for clearness of understanding only, and no unnecessary limitations should be understood therefrom, but the appended claims should be construed as broadly as permissible in view of the prior art. 45

What I regard as new, and desire to secure by Letters Patent, is—

1. A golf club comprising an angular club-head, and a shaft comprising a tubular handle-section of relatively large diameter which is provided with a downwardly tapering lower end portion, and a shaft-section of smaller diameter having its lower end secured to the club-head and having its upper end expanded and provided with a downward taper, said sections being of substantially equal length and in telescoped relation when the club is collapsed and said expanded portion being operative to bind the sections together by inertia of one part when the other is moved with relation thereto. 55

2. A golf club comprising a tubular handle-section provided with a downwardly tapering lower end portion, a wooden shaft-section having a reduced extremity extending into said handle and equipped with a downwardly tapering ferrule, said reduced extension being expanded within said ferrule, and an angular club-head secured to the lower end of said wooden shaft-section, said sections being of approximately equal 70 length and adapted to telescope with relation to each other and said sections being adapted to be securely bound together in the extended position by action of inertia. 75

CHARLES FISHER.
